UNITED STATES PATENT OFFICE.

LEW ARNTZ, OF DES MOINES, IOWA.

ATTACHMENT FOR EYEGLASS-MOUNTINGS.

1,266,757.

Specification of Letters Patent. Patented May 21, 1918.

Application filed December 20, 1917. Serial No. 208,192.

To all whom it may concern:

Be it known that I, LEW ARNTZ, a citizen of the United States, and resident of Des Moines, in the county of Polk and State of Iowa, have invented a certain new and useful Attachment for Eyeglass-Mountings, of which the following is a specification.

The object of my invention is to provide an attachment for an eye-glass mounting so constructed and arranged as to permit the quick and easy installation or removal of the finger piece lever, which carries a nose clamp or guard.

Still a further object is to provide in an eye-glass mounting a means for supporting a finger piece lever comprising a post capable of being locked in two positions, in connection with a finger piece lever so constructed and arranged as to be locked on 20 said post when the post is in one position and to be readily removed from the post when the post is in another position.

With these and other objects in view, my invention consists in the construction, arrangement and combination of the various parts of my device, whereby the objects contemplated are attained, as hereinafter more fully set forth, pointed out in my claims and illustrated in the accompanying drawings, in which:

Figure 1 shows a front elevation of an eye-glass mounting embodying my invention, the guard or nose clamp, pad, finger piece lever, finger piece and spring being omitted from one side.

Fig. 2 shows a vertical sectional view taken on the line 2—2 of Fig. 1, and

Fig. 3 shows a top or plan view of the sleeve mounting on the upright post.

In the accompanying drawing I have used the reference numeral 10 to indicate in general the bridge of an eye-glass mounting having at its opposite ends the braces 11, which engage the edges of the lenses and 45 the lens ears 12, which may be of any suitable construction.

Between the curved portions of the bridge 10 and the braces 11 are substantially straight portions 13. In the straight portions 13 are substantially vertical openings 14, which are screw threaded to receive a screw threaded portion 15 of an upright post 16. On the lower end of each post 16 is a small nut or head or other stop device 17.

On each post 16 above the portion 13 is a collar or flange or the like 18. The dis-

tance between the collar 18 and the nut 17 is greater than the thickness of the portion 13, so that when the post 16 is screwed to the limit of its movement in one direction, 60 the nut 17 will engage the portion 13 for locking the post against movement and when the post is screwed in the other direction approximately a quarter turn the collar 18 engages the portion 13 for locking the post 65 against movement as illustrated at the right hand side in Fig. 1. It thus appears that the post can be locked in two positions and the parts are preferably so arranged that the range of movement of the post is about 70 a quarter turn.

The upper end of each post 16 is provided with a slot 19 to receive a screw driver. Each post 16 is provided near its upper end with a laterally extending pin 20.

For eye-glass mountings of the type shown herein I have provided guards provided with special parts or equipment. In Fig. 1 I have shown a guard 21 having the ordinary pad 22. Connected with the guard 21 80 is the finger piece lever 23. The lever 23 has at one end the ordinary finger piece 24. On the finger piece lever 23 is a drum shaped sleeve 25 designed to be slidably and rotatably received on the post 16 and provided with a central opening or bore 26 to receive the post 16. The sleeve 25 is provided with the vertically elongated slot 27 opening into the bore 26 and adapted to permit the passage of the pin 20 in mounting the sleeve 25 on the post 16. Mounted on each drum shaped sleeve 25 is a spring 28. One end of each spring 28 is suitably bent at 29 to engage the finger piece lever 23 and the other end of the spring 28 is 95 designed to engage one of the brace members 11 as illustrated in Fig. 1 so as to give the spring 28 its ordinary function.

It will be noted that the construction of my mount is such that guards of different 100 kinds may be selectively mounted upon the portions 13. In the practical installation of one of said guards the post 16 is moved to one limit of its movement by means of a small screw driver to position to permit 105 a sleeve 25 to be dropped downwardly over the post and to permit the pin 20 to slide freely through the slot 27. When the sleeve 25 rests on the collar 18 and the spring 28 is arranged with one end engaging one of 110 the braces 11 the post 16 is given a quarter turn to cause the pin 20 to be moved to such

position that the sleeve 25 cannot be moved to position where the pin 20 registers with the slot 27. The post 16 is locked by frictional engagement of the nut 17 or the collar 18 as the case may be with the member 13 and the guard cannot be moved to position to permit its removal on account of the fact that the guard engages the bridge 10, which limits its movement in one direction 5
10 while the spring yieldingly limits the movement of the guard in the other direction and the members 11 absolutely limit such movement in the other direction. It will thus be seen that one of the interesting features 15 about my invention is the fact that the post 16 is locked with the pin 20 projecting in such direction that the sleeve 25 cannot be removed.

The advantages of my improved mounting may be largely seen from the foregoing description. The advantage of my device over a mounting having a guard secured to the member 13 or its equivalent by a post screwed into the member 13 in 20 the ordinary way or riveted thereto is obvious. The guards of my mounting may be very quickly and easily removed and replaced with others thereby greatly reducing the work and time necessary for properly fitting glasses to the patient. 25

Some changes may be made in the construction and arrangement of the various parts of my improved mounting without departing from the essential features and 30 purposes of my invention and it is my intention to cover by my claims any modified forms of structure or mechanical equivalents, which may be reasonably included within their scope.

40 I claim as my invention:

1. The combination of an eye-glass mounting having a bridge provided with substantially oppositely extending members at its ends, brace members on said first members, 45 posts mounted in said oppositely extending members by screw threaded connections, stop devices on said posts above and below said oppositely extending members for permitting limited rotary movement of said 50 posts and for locking them in different positions of their movement, laterally extending pins on said posts, a guard for each post including a finger piece lever, each having a sleeve rotatably and slidably mounted on one of said posts, said sleeve being provided with a bore and with a slot 55

opening into said bore and adapted to slidably receive one of said pins, the parts being so arranged that when said posts are at one limit of their movement, the pins on the 60 posts register with said slots and when the posts are at another limit of their movement the sleeves cannot be moved to position where their slots register with said pins. 65

2. A mounting comprising the combination of a bridge having at its ends substantially horizontal extensions, posts mounted in said extensions for limiting rotary movement, said posts and said extensions having means 70 whereby they may be locked at their different limits of movement, laterally extending pins on said posts, guards each comprising a finger piece lever, a sleeve on said finger piece lever having a central bore for 75 receiving one of said posts, and a slot opening into said bore for permitting the passage of one of said pins, the parts being so arranged that at one limit of movement of the post one of said sleeves may be mounted 80 on the post with the pin on said post registering with the slot in the sleeve while in another position of said post the sleeve cannot be moved to such position that the slot therein will register with said last 85 named pin.

3. A mounting comprising the combination of a bridge having at its ends substantially horizontal extensions, posts mounted in said extensions for limiting rotary movement, said posts and said extensions having means whereby they may be locked at their different limits of movement, laterally extending pins on said posts, guards each comprising a finger piece lever, a sleeve on said 90 finger piece lever having a central bore for receiving one of said posts, and a slot opening into said bore for permitting the passage of one of said pins, the parts being so arranged that at one limit of movement of the post one of said sleeves may be mounted 95 on the post while in another position of said post, the sleeve cannot be moved to such position where the slot therein will register with said pin, said sleeve being 100 drum shaped, and a spring mounted on said sleeve having one end arranged in engagement with said finger piece lever, and the other end adapted to engage the brace on the mounting. 105

Des Moines, Iowa, November 13, 1917.
LEW ARNTZ.
